CLAIM

The ornamental design for a lighting fixture component, as shown and described.

DESCRIPTION

FIG. 1 is a front perspective view of a lighting fixture component depicting a new design;
 FIG. 2 is a back perspective view thereof;
 FIG. 3 is a front elevation view thereof;
 FIG. 4 is a left elevation view thereof;
 FIG. 5 is a right elevation view thereof;
 FIG. 6 is a bottom plan elevation view thereof;

FIG. 7 is a front perspective view thereof that shows the lighting fixture component in an environment of use; and,
 FIG. 8 is a back perspective view that shows the lighting fixture component in an environment of use.
 The broken line disclosures in FIGS. 7 and 8 represent environment which forms no part of the claimed design. The remaining broken line disclosures in the views represent portions of the lighting fixture component that form no part of the claimed design.
